UNITED STATES PATENT OFFICE

EUGENE LEVERING SCHELLENS, OF POINT CLAIRE, QUEBEC, CANADA, ASSIGNOR TO
FRANKLIN RAILWAY SUPPLY COMPANY, A CORPORATION OF DELAWARE

POWER AMPLIFYING MACHINE

Original application filed December 15, 1924, Serial No. 756,160. Divided and this application filed August 31, 1925. Serial No. 53,624.

The invention relates to a power amplifying machine, as described in the present specification and illustrated in the accompanying drawings that form part of the same.

5 The invention consists essentially of the novel features of construction pointed out broadly and specifically in the claims for novelty following a description containing an explanation in detail of an acceptable form 10 of the invention.

The objects of the invention are to insure even pressures and closed ports following each operation; to avoid slippages of the pressures; to inspire the engineer-in-charge 15 with confidence in the operation of the reverse gear and thereby save damage to life and property; to utilize for accuracy a screw operating means originally disclosed in Letters Patent of the United States Number 20 1,476,470 of December 4, 1923 and filed November 5, 1919 in another form; and generally to provide an efficient, durable and serviceable mechanism in a power amplifying 25 machine.

In the drawings, Figure 1 is a longitudinal sectional view of the cylinder and piston, showing the valve chamber, valve and screw operating gear.

30 Figure 2 is an enlarged sectional detail showing the plan of the controlling valve and its operating mechanism.

Figure 3 is a view of the complete gear, certain parts of the cylinder and piston being broken away to show the connection of 35 the reach rod to the piston.

Like numerals of reference indicate corresponding parts in the various figures.

Referring to the drawings, the cylinder 40 40 contains a differential trunk piston 41 and the trunk of this piston is of lesser diameter than the head 42 rigidly secured to the trunk, consequently there is an annular chamber 43 between the trunk and the cylinder wall, 45 which is the constant pressure chamber, this chamber being continuously connected to the fluid supply through the inlet 44.

The valve mechanism is contained in the head 42 and for this purpose a central chamber 45 50 is formed which extends inwardly in

the direction of the trunk bridge 46 from which the reach rod lug extends.

The variable pressure chamber 47 is connected by the port 48 through the valve chamber 45 with the constant pressure chamber 43, the said port 48 extending in an angular course through the head. A port 49 communicates with the valve chamber and the interior of the trunk piston through which the pressure fluid escapes from the variable pressure chamber 47 to the atmosphere. 60

The valve 50 which is of the slide type controls the passage of fluid through the ports 48 and 49 and slides longitudinally to uncover the same, said valve being held to its seat 65 by the pin 51, which is resiliently held thereto by the spring 52 through the squared end 53 of the lead screw 54, said squared end engaging the valve 50 by means of the boss 55 from the valve projecting into a corresponding recess into the squared end of the screw. 70

Between the trunk of the piston 41 and the head 42 the packing 57 is held in a recess 58 by the ring 59, which keeps said packing to its engagement with the cylinder wall. 75

The sleeve 61 encloses the screw 54 and is screwed on to the nut 62, which operates on the lead screw 54 for moving the latter.

The nut 62 is flanged at 63 and turns in the cylinder head 64 within the central circular opening 65 in the head on the flange 66, which extends outwardly and contains the ball bearings 67 and packing 68 that are held in by the spring 69 and cap 70. 80

The cylinder head 64 is secured to the cylinder in any suitable manner, both having finished faces meeting at 71. The faucet 72 controls the drain opening 73 and is adapted to be used in clearing the variable pressure chamber from the effects of condensation. 85

The valve chamber 45 is shown as closed by the screw cap 74 and is preferably squared inwardly beyond the cap threading though not necessarily so.

The other end of the cylinder 40 is closed by the annular cap 75 forming a bearing for the trunk of the piston and packed at 76 against the flange 77, said cap having the inlet 44 mentioned hereinbefore. 95

The sleeve 61 is coupled to the universal 100

joint 78 operated by a wheel 79 and this enables the engineer to turn said wheel and thereby rotate the nut and propel the lead screw and the valve engaged with its squared end.

5 The operation of the gear will be clear from the following:

Assuming that the pressures on each side of the piston head are so balanced as to retain the piston stationary, and it is desired 10 to move the piston to the left, the sleeve 61 and the nut 62 are rotated (by the hand wheel 79) to move the lead screw 54 and valve 50 to the left. This uncovers the port 48 allowing fluid pressure to pass from the chamber 43 to the chamber 47 until the pressure is increased in the latter chamber sufficiently to move the piston to the left until the piston moves far enough to reclose the 15 port 48. When it is desired to move the piston to the right the lead screw and valve is moved to the right. This opens the port 49 to the valve chamber 45 and establishes communication between the chamber 47 and the 20 interior of the trunk to the atmosphere. Fluid will now be exhausted from the chamber 47 until the pressure is reduced sufficiently to allow the pressure in the annular chamber 43 to move the piston to the right. This 25 movement acts to reclose the port 49 and re-establish the balanced condition.

If, during a movement of the piston, the piston moves far enough to close the port being used for the movement and cause the 30 valve to uncover the other port to the valve chamber, the chamber 47 will have communication either with the atmosphere or the chamber 43, depending on the direction of movement, and the pressures will automatically be balanced.

40 This application is a division of my co-pending application Serial No. 756,160, filed December 15, 1924.

What I claim is:

45 1. In apparatus of the character described, the combination of a control valve, and means for actuating the same including a lead screw having a portion having a flattened surface engaging said valve to prevent rotation of the 50 said screw and a nut member, together with means for manually rotating said nut member to move said lead screw.

55 2. Apparatus of the character described comprising a cylinder, a piston, a control valve in the piston head, a lead screw engaging said valve, means for holding said lead screw as against rotation, and means for moving said lead screw longitudinally.

60 3. Apparatus of the character described comprising a cylinder, a piston, a control valve in the piston head, a lead screw engaging said valve, means for holding said lead screw as against rotation, and means for moving said lead screw longitudinally comprising a 65 manually rotatable sleeve member and a

nut member secured thereto and engaging said lead screw.

4. Apparatus of the character described comprising a cylinder, a trunk piston movable therein dividing said cylinder into an 70 annular and a cylindrical chamber, a valve chamber in the piston head communicating with said cylindrical chamber, a valve seat in said valve chamber having a port communicating with said annular chamber and a 75 port communicating with the atmosphere through the piston trunk, and a slide valve movable on said seat to control said porting, together with a lead screw fixed as against rotation for actuating said valve.

5. Apparatus of the character described comprising a cylinder, a trunk piston movable therein dividing said cylinder into an annular and a cylindrical chamber, a valve chamber in the piston head communicating with said cylindrical chamber, a valve seat in said valve chamber having a port communicating with said annular chamber and a port communicating with the atmosphere through the piston trunk, and a slide valve 80 movable on said seat to control said porting, together with valve actuating means comprising a lead screw having a squared portion engaging said valve.

6. Apparatus of the character described 95 comprising a cylinder, a trunk piston movable therein dividing said cylinder into an annular and a cylindrical chamber, a valve chamber in the piston head communicating with said cylindrical chamber, a valve seat 100 in said valve chamber having a port communicating with the annular chamber and a port communicating with the atmosphere through the piston trunk, and a slide valve movable on said seat to control said porting, together with valve actuating means comprising a lead screw having a squared portion 105 engaging said valve, and means for moving said lead screw longitudinally including a manually rotatable nut member engaging 110 said lead screw.

7. Apparatus of the character described comprising a cylinder, a piston, a control valve in the piston head, and a valve actuating lead screw extending through the cylinder head, and means for moving said lead screw longitudinally comprising a manually rotatable nut member mounted for rotary motion in said cylinder head together with means for preventing rotation of said lead 115 screw.

8. A fluid pressure operated power reverse gear comprising, in combination, a cylinder, a piston, a slide valve in the piston head having porting for controlling the operating fluid, and a valve actuating lead screw extending through the cylinder head and engaging said slide valve to prevent rotation of the screw together with means comprising a 120 manually rotatable nut member mounted in 125 a

5 said head for moving said lead screw longitudinally.

9. A fluid pressure operated power reverse gear including, in combination, a cylinder, a piston, and a control valve structure in the piston head having porting for controlling the operating fluid, said structure including a valve mounted in the piston head for reciprocating movement but being fixed as against 10 rotation therein, together with valve actuating means including a member having a threaded portion extending through a cylinder head, and a cooperating threaded and rotatable part for moving said member longitudinally, the said member being fixed as 15 against rotation by engagement with said valve.

Signed at Montreal, Canada, this 28th day of July 1925.
